UNITED STATES PATENT OFFICE.

GEORGE W. STEVENSON, OF CANTON OHIO.

FURNACE.

1,223,213.

Specification of Letters Patent. Patented Apr. 17, 1917.

Application filed August 22, 1916. Serial No. 116,347.

To all whom it may concern:

Be it known that I, GEORGE W. STEVENSON, a citizen of the United States, residing at Canton, in the county of Stark and State 5 of Ohio, have invented new and useful Improvements in Furnaces, of which the following is a specification.

This invention relates to furnaces especially adapted to be used for heating metal 10 plates or bars preparatory to rolling and it consists in the novel features hereinafter described and claimed.

An object of the invention is to provide a furnace of the character indicated which in 15 turn includes side and top walls with a fire box located at the center thereof and a wheel journaled for rotation within the wheels and surrounding the fire box. Novel and improved means are provided for turning 20 the said wheel and the wheel is supported upon ball bearings which are immersed in water and the said turning means are also submerged whereby they are protected against the intense heat and prevented from 25 becoming annealed.

A number of heating chambers or compartments are arranged upon the wheel and the said compartments are separated from each other by means of walls or partitions 30 which include fire brick casings and fillings of sand or other granular material.

The furnace is substantially circular in plan and it is surrounded at its face by a flue which communicates with a stack. 35 Other flues are provided at the sides of the furnace and they communicate at their lower ends with the first mentioned flue and at their upper ends with the interior of the furnace. Openings are provided at the upper end of the fire-box whereby the products 40 of combustion may pass from the firebox into the interior of the furnace above the wheel. The said products of combustion pass down through the flues and through the 45 circular flue stack.

In the accompanying drawings:—

Figure 1 is a top plan view of the furnace.

Fig. 2 is a side elevation of the same.

Fig. 3 is a horizontal sectional view of 50 the same.

Fig. 4 is a transverse vertical sectional view of the same.

Fig. 5 is an enlarged fragmentary horizontal sectional view.

Fig. 6 is a perspective view of a bearing 55 used in the furnace.

Fig. 7 is a side view of a ball used in the same.

The furnace includes an exterior circular wall 1 of fire brick or other suitable material, the said wall 1 supporting the roof 2 of similar material. Beams 3 are positioned at the exterior surface of the wall 1 and rods 4 connect the upper ends of the beams with a ring 5 which is positioned at the central portion of the roof 2. A circular flue 6 surrounds the base portion of the wall 1 and the said flue communicates with the base of a stack 7. Upright flues 8 communicate at their lower ends with the flue 6 and at their upper ends with the interior of the furnace body. A fire-box 9 is concentrically positioned in the body of the furnace and the said fire-box is provided at its upper end with openings 10 which communicate with the interior of the body of the furnace. A grate 11 is located in the lower portion of the fire-box 9 and an ash pit 12 is provided below the said grate. A tunnel 13 communicates at one end with the side of the ash pit 12 and leads under the body of the furnace and is provided at its outer end with a door 14 of usual pattern. A hopper 15 is mounted at the center of the roof 2 and a gate 16 is slidably mounted in the lower portion of the said hopper. A lever 17 is fulcrumed upon the roof 2 of the furnace and one end thereof is connected with the said gate. A rod 18 is connected with the outer end of the said lever 17 and may be used for swinging the lever whereby the gate may be moved from a closed to an open position in the hopper or vice versa.

The wall 1 is provided at one side with a door opening 19 and vertically disposed guides 20 are positioned at the side edges thereof. A skid 21 is positioned at the side of the wall 1 below the door opening 19 and a door 22 is slidably mounted in the guides 20. A lever 23 is fulcrumed upon the wall 1 above the door opening 19 and a chain 24 connects one end of the said lever 23 with the door 22. Another chain 25 is attached to the free end of the lever 23 and may be used for swinging the lever. As the lever is 100 swung the chain 24 is moved longitudinally whereby the door 22 may be opened or closed with relation to the opening 19.

A steam pipe 26 leads into the flue 6 at a point adjacent the base of the stack 7 and 110 may be used for injecting steam into the flue and stack for the purpose of starting a

draft through the same. A damper 27 is located in the flue 6 adjacent the steam pipe 26 and may be moved to increase or diminish the passage way through the said flue and 5 stack to regulate the draft through these parts.

A number of bearings 29 are mounted upon the bottom wall 30 of the furnace and balls 31 are provided with gudgeons 32 10 which are journaled in the said bearings 29.

The lower portion of the body of the furnace is filled with water the level of which is above the balls 31 and the bearings which support the same. A wheel 33 is provided at 15 its underside with races 34 which receive the balls 31 and the said wheel is arranged to turn within the side wall 1 of the furnace and around the fire box 9 thereof. A chain or other flexible elements 35 surrounds the 20 periphery of the wheel 33 and also winds about a drum 36 mounted on a shaft 37 journaled for rotation in a basin 38 provided at the side wall 1 of the furnace. A gear wheel 39 is mounted on the shaft 37 and meshes 25 with a gear wheel 40 mounted on a shaft 41 also journaled in the said basin. A beveled pinion 42 is mounted on the shaft 41 and meshes with a similar pinion 43 mounted on a shaft 44 journaled for rotation 30 above the basin 38. The shaft 44 is provided with a crank handle 45 whereby the said shaft may be rotated. It is apparent that as the shaft 44 rotates the beveled pinions transmit rotary movement to the 35 shaft 41 which through the intermeshing gear wheels 39 and 40 move the chain 35 longitudinally and consequently the wheel 33 is rotated about the fire box of the furnace.

A number of sector shaped partitions 46 40 are mounted upon the wheel 33 and the spaces between the said partitions form heating chambers 47. The said partitions 46 are filled with sand 48 or other suitable granular material and quantities of sand are contained below the floor of the heating chambers 45 as best indicated in Fig. 4 of the drawing. The floors of the heating chambers 47 are provided with longitudinally disposed grooves 49 along which tongs or 50 other suitable handling implements may be passed when it is desired to withdraw the plates of metal or bars from the heating chambers.

In operation, the products of combustion 55 pass from the fire box 9 through the openings 10 at the upper portion thereof into the space under the roof 2 of the furnace. The said products of combustion then descend and pass down through the flues 18 into the 60 flue 6 and then around the flue 6 and up through the stack 7. During this movement

of the products of combustion the heat comes in contact with the material which is located in the heating chambers 47 and the said material is heated preparatory to rolling or 65 working. Also the sand 48 absorbs a great amount of heat and gives the same off gradually so that when the furnace is once thoroughly heated the plates or bars which are placed in the heating chambers 47 are 70 soon brought to a desired degree of temperature. When the material is placed in the heating chambers an operator uses the crank 45 whereby the wheel is turned and the material is carried around the interior 75 of the wall 1. As the heated material arrives at the door opening 19 it is removed from the furnace through the same and other material to be heated is placed in the heating chambers through the said door openings. 80

From the foregoing description taken in connection with the accompanying drawing, it will be seen that a furnace of simple and durable structure is provided and that the same may be economically used for the 85 purpose of heating plates of metal or bars preparatory to rolling or other operation.

What I claim is:—

1. A furnace comprising a side wall, a top wall and a bottom wall, a basin located at 90 the side of the furnace and communicating with the interior thereof through an opening in the side wall, the upper end of the basin being at an elevation sufficiently high to hold water against the upper edge of the 95 said opening, a wheel turnably mounted in the furnace, a fire box positioned centrally of the wheel, the lower portion of the furnace constituting a tank adapted to retain water from the basin, means for turning the wheel 100 and immersed in the said water, a flue surrounding the base portion of the furnace, other flues communicating with the interior of the furnace and the first mentioned flue, and a stack communicating with the last 105 mentioned flue.

2. A furnace comprising a body having a centrally positioned fire box and adapted to retain a liquid cooling agent, bearings located in the lower portion of the body and 110 adapted to be immersed in said agent, anti-friction members journaled in the bearings, a wheel having races which receive the anti-friction members, partitions mounted upon the wheel, a flexible element connected with the wheel, a drum around which the said flexible element is wound and means immersed in said cooling agent and adapted to turn the drum.

In testimony whereof I affix my signature. 120

GEORGE W. STEVENSON.
